(57) **CLAIM**

The ornamental design for a folding, low profile tripod base.

DESCRIPTION

FIG. 1 is a front top perspective view of a folding, low profile tripod base shown in the expanded configuration.

FIG. 2 is a front elevational view of the tripod base shown in FIG. 1.

FIG. 3 is a rear side elevational view of the tripod base shown in FIG. 1.

FIG. 4 is a left side elevational view of the tripod base shown in FIG. 1.

FIG. 5 is a right side elevational view of the tripod base shown in FIG. 1.

FIG. 6 is a top plan view of the tripod base shown in FIG. 1.

FIG. 7 is a bottom plan view of the tripod base shown in FIG. 1.

FIG. 8 is a front top perspective view of the tripod base shown in FIG. 1 in a folded configuration.

FIG. 9 is a front elevational view of the tripod base shown in FIG. 8.

FIG. 10 is a front top perspective view of the tripod base shown in FIG. 8.

FIG. 11 is a top elevational view of the tripod base shown in FIG. 8; and,

FIG. 12 is a bottom plan view of the tripod base shown in FIG. 8.
